(57) **CLAIM**

I claim the ornamental design for a pan rack frame, as shown and described.

DESCRIPTION

FIG. 1 shows a frontal perspective view of the pan rack frame.

FIG. 2 is a top plan view.

FIG. 3 is a bottom plan view.

FIG. 4 is a left side elevation view.

FIG. 5 is a right side elevation view.

FIG. 6 is a front elevation view.

FIG. 7 is a rear elevation view.

FIG. 8 is a view showing the pan rack frame in the environment in which it is used.

FIG. 9 is a frontal perspective view of an alternative embodiment of the pan rack frame.

FIG. 10 is a top plan view of the alternative embodiment.

FIG. 11 is a bottom plan view of the alternative embodiment.

FIG. 12 is a left side elevation view of the alternative embodiment.

FIG. 13 is a right side elevation view of the alternative embodiment.

FIG. 14 is a front elevation view of the alternative embodiment.

FIG. 15 is a rear elevation view of the alternative embodiment; and,

FIG. 16 is a view showing the alternative embodiment in the environment in which it is used.

1 Claim, 10 Drawing Sheets
